A. O. TRUELSON,
MUFFLER EXHAUST DEFLECTOR,
FILED AUG. 16, 1921.

Inventor
Arthur Oscar Truelson

UNITED STATES PATENT OFFICE.

ARTHUR OSCAR TRUELSON, OF ALHAMBRA, CALIFORNIA.

MUFFLER-EXHAUST DEFLECTOR.

Application filed August 16, 1921. Serial No. 492,853.

To all whom it may concern:

Be it known that I, ARTHUR OSCAR TRUELSON, a citizen of the United States, residing at 25 North Vega Street, city of Alhambra, 5 county of Los Angeles, State of California, have invented a new and useful Muffler-Exhaust Deflector, to be used on Ford automobiles for the purpose of diverting the flow of exhaust gases from the spare tire 10 and rear of the car, of which the following is a specification.

My invention relates to a tubular steel deflecting body, the top of which is sealed, an opening being made in the edge of the 15 body, near the top, to receive the exhaust gases from the muffler. The bottom of the body is open to discharge the exhaust gases.

My invention comprises a hook arrangement to fasten the steel body to the exhaust 20 end of the muffler without any changes in the opening of the muffler used on the year 1921 and subsequent models of the Ford automobile. The slot in the end of the steel body is so arranged in punching as to form 25 two permanent lugs to hold the body in proper position when inserted in the exhaust slot of the muffler. A hook bolt is so arranged between the two permanent lugs that, when turned to the right or left, it will 30 clamp to the flange on the inside of muffler head. Then, by tightening the nut, the hook bolt will lock the body to the muffler head.

I attain these objects by the mechanism 35 illustrated in the accompanying drawings in which:

Figure 1 is a detailed view showing the exhaust end of a muffler and deflector attached thereto, parts being broken away.

Figure 2 shows the permanent lug and 40 hook bolt locking the deflector to the muffler head.

Figures 3 and 4 show the exhaust end of a Ford muffler.

Figure 5 is a side elevation of a complete 45 Ford muffler with the deflector attached.

Number 1 refers to bracket on muffler head to bolt muffler to chassis of car.

Number 2 refers to rivets to hold bracket to muffler head.

Number 3 muffler head, exhaust end.

50

Number 4 deflector, tubular steel body.

Number 5 washer on hook bolt.

Number 6 nut on hook bolt.

Number 7 hook bolt.

Number 8 and 8 permanent lugs on tubu- 55 lar steel body.

Number 9 muffler shell.

Number 10 hook on end of bolt.

Number 11 exhaust opening of deflector 60 body.

Number 12 exhaust slot, thru which the muffler discharges into the air.

Number 13 inside of tubular steel body.

Number 14 exhaust pipe from engine to 65 muffler.

Number 15 intake head of Ford automobile muffler.

What I claim is:

1. A deflector for an exhaust muffler, comprising a deflecting body having an opening 70 to register with the muffler outlet opening, and extensions on said body, to enter said outlet opening and co-operate with the muffler wall to retain the deflector in place.

2. A tubular exhaust deflector for auto- 75 mobile muffler having an exhaust outlet, comprising a hollow body adapted to be readily attached to the exhaust outlet of the muffler, means for attaching the deflector to the muffler comprising lugs on the deflector 80 and a hook bolt carried by said deflector and adapted to engage the interior of said muffler, opening in said deflector, one at the side for the admission of the exhaust gases to the deflector from the muffler and 85 one at the end of said deflector for the escape of the exhaust gases therefrom.

ARTHUR OSCAR TRUELSON.
